OIL APPLICATOR

Norval Ray Kelly, Douglaston, Long Island, N. Y.

Application August 27, 1936, Serial No. 98,262

3 Claims. (Cl. 132—1)

This invention relates to new and useful improvements in an oil applicator.

The invention has for an object the construction of an applicator which is characterized by a hollow shell having an open bottom side into which a sponge holding shell may be engaged a limited distance, and an arrangement whereby oil placed within said hollow shell passes through and reaches a sponge within said sponge holder.

As a further object of the invention it is proposed to form the inner wall of the holding shell with perforations for the passage of the oil from the hollow shell to the sponge.

Another object of the invention is to produce a cap for engaging over the sponge and enclosing it when the device is not in use.

Another one of the objects of this invention resides in the provision of an annular bead around the hollow shell for constituting the means to limit the engagement of the sponge holding shell within the hollow shell and simultaneously constituting a stop for an outer cap which is used to cover the sponge.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of an oil applicator constructed according to this invention.

Fig. 2 is a transverse vertical sectional view of Fig. 1.

Fig. 3 is a perspective view of the sponge holding shell and associated parts per se.

Fig. 4 is a bottom plan view of Fig. 3.

Fig. 5 is a perspective view of the sponge covering cap.

Fig. 6 is a similar view to Fig. 4 but showing another form of the device.

Fig. 7 is a perspective view of the oil applicator, according to the form illustrated in Fig. 6.

The oil applicator, according to this invention, comprises a hollow shell 10 of composition or any other suitable material, having an open bottom side and a top side with an inlet 11 closed with a removable cap 12. A sponge holding shell 13 is adapted to engage a limited distance into the open bottom of the hollow shell 10. A sponge 14 is arranged in the outer side of the sponge holding shell. The inner wall 15 of said sponge holding shell 13 is formed with perforations 16

for the passage of oil from the hollow shell to the sponge.

The cap 12 is screw threaded upon a projecting portion constituting the inlet 11. It may be removed and the oil or other liquid engaged into the hollow shell when desired. The side walls of the shell 10 are formed with an annular bead 18 which has a dual purpose. One is that it acts as a stop for limiting the engagement of the sponge holding shell 13. Secondly, it acts as a stop for an external shell 19. This external shell 19 is in the form of a cap adapted to engage over and cover the sponge 14.

Rubber or other soft resilient material 20 is interposed between certain of the contacting surfaces of the sponge holding shell 13 and the hollow shell 10 so as to provide a liquid proof joint and prevent the seeping of the oil between these parts. Thus, the oil is caused to travel through the perforations 16.

A means is provided for controlling the operative size of the perforations 16. This means includes a disc 22 which is rotatively mounted upon the wall 15 by reason of a central pintle rivet 23. This disc is formed with perforations 16^a adapted in one position of rotation of the disc to align with the perforations 16. A lug portion 24 is stamped from the material of the disc 22 and extends upwards and engages into a stationary clip 25 which is mounted upon a shell 10. This clip 25 has a pair of fingers adapted to engage on opposite sides of the lug 24 and so hold it in position. The arrangement permits the shell 10 to be slightly turned relative to the sponge holding shell 13 for aligning or partially aligning the openings 16^a and 16.

The operation of the device is as follows:

Oil such as sun tan oil, or other liquid, may be placed into the hollow shell 10 by first removing the cap 12. This liquid may seep through 40 on the sponge 14 and may be applied to one's skin by patting the sponge thereon. When the device is not in use the cap 19 is engaged upon the lower portion of the hollow shell 10.

In Figs. 6 and 7 modified shape of shells 10' 45 and 19' have been illustrated. The shape of the sponge 14' corresponds with the shape of the shells.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. An oil applicator comprising a hollow shell having an open bottom side and a top side with a cap inlet for oil and other liquids, a sponge holding shell engaged a limited distance in the open bottom of said hollow shell, a sponge in the outer side of said hollow shell, the inner wall of said hollow shell being perforated for the passage of oil and liquids from the hollow shell to the sponge, and means for controlling the seepage of the oil and liquids through said perforations, comprising a perforated disc rotatively mounted upon said inner wall and having apertures adapted to align with or be out of alignment with said perforations, said disc having a projecting element engageable with a stationary member upon said hollow shell, whereby the hollow shell may be turned relative to the sponge holding shell for moving the disc relative to said inner wall.
2. An oil applicator comprising a hollow shell having an open bottom side and a top side with a cap inlet for oil and other liquids, a sponge holding shell engaged a limited distance in the open bottom of said hollow shell, a sponge in the outer side of said hollow shell, the inner wall of said hollow shell being perforated for the passage of oil and liquids from the hollow shell to

the sponge, and means for controlling the seepage of the oil and liquids through said perforations, comprising a perforated disc rotatively mounted upon said inner wall and having apertures adapted to align with or be out of alignment with said perforations, said disc having a projecting element engageable with a stationary member upon said hollow shell, whereby the hollow shell may be turned relative to the sponge holding shell for moving the disc relative to said inner wall, said latter-mentioned member comprising a cap with a pair of fingers engaging against the opposite sides of said element. 5

3. In an oil applicator, a hollow casing having an open bottom side, a sponge holding shell engaging into said open bottom side and having apertures, a disc rotatively mounted upon the outer top side of said shell and having apertures alignable with said apertures, a projecting element mounted on one side of said disc and extending into said casing, a stationary member mounted within said casing, and depending finger portions on said stationary member engaging over said projecting element, whereby said cover may be rotated to move said projecting element 10 and said disc to control the operative size of said apertures. 15
